UNITED STATES PATENT OFFICE.

PULASKI J. COOLEY, OF CHICAGO, ILLINOIS.

CARPENTER'S SQUARE.

No. 895,241.

Specification of Letters Patent.

Patented Aug. 4, 1908.

Application filed November 25, 1907. Serial No. 403,626.

To all whom it may concern:

Be it known that I, PULASKI J. COOLEY, a citizen of the United States, residing in the city of Chicago, county of Cook, and State of Illinois, have invented a certain new and useful Improvement in Carpenters' Squares, of which the following is a specification.

This invention relates to carpenters' squares. Its principal objects are to make a square separable into parts in such a manner that it can be readily taken apart for the purpose of more convenient carrying, and in order that it may be placed into a comparatively small box; and also to provide means to join the several parts firmly and accurately together, and to cheapen construction. I attain these objects by the means illustrated in the accompanying drawing, in which

20 Figures 1 and 2 are plan views of two different constructions of my improved square fully assembled; while Figs. 3, 4 and 5 are enlarged sectional views, on the lines 3—3, 4—4, and 5—5, of the parts shown in Fig. 1.

25 Referring to the drawings, blades 7 and 8 of my improved square are joined together by rectangular member 9, the connection between said blades and member 9 being made by tongues 10 and 11 (of blades 7 and 8 respectively) which are preferably constructed with a slight taper from their bases towards their ends, and fit into corresponding grooves 12 and 13 (cut lengthwise in the larger and smaller arms of member 9 respectively) the

30 margins 15 of which are undercut to correspond to dovetailed edges 16 of tongues 10 and 11. To reduce cost of manufacture I prefer to run groove 12 the whole length of the larger arm of member 9, and to run

40 groove 13 from groove 12 to the end of the smaller arm of member 9. To secure smoothness of surface of the square I either form the end of tongue 11 with an undercut edge, corresponding to margins 15, so as to

45 fit the dovetailed edge of tongue 10, or form the end of tongue 11 square while cutting away the abutting portion of tongue 10. In this latter form of construction (shown in Fig. 2.) tongue 11 should be made long

50 enough to project (when the square is assembled) into tongue 10, thus serving to

lock tongue 10, and with it blade 7, in position. In all cases blades 7 and 8, where tongues 10 and 11 are projecting from them, and the respective opposite ends of member 9 are formed of such thickness, width and shape as to mutually correspond in these particulars, so as to make close fitting joints and a smooth continuous surface over the whole square when assembled. Tongues 10 and 11 are preferably made of about one-half the thickness of blades 7 and 8, and shoulders 17 at the juncture of tongues 10 and 11 to blades 7 and 8 respectively, are made rounded to prevent easy breaking at this point of weakness.

To more firmly hold the parts together in assembled position, locking screws 19 are provided the heads of which fit into countersunk holes in member 9, and the threaded points of which engage corresponding threads in tongues 10 and 11 respectively. In the construction shown in Fig. 1. two of such screws are employed, one for each tongue; while in the construction shown in Fig. 2. only one such screw is used, for the purpose of locking tongue 11 in position.

What I claim as my invention, and intend to secure by Letters Patent, is:—

1. In a separable square; the combination 80 of a right angled connecting member having grooves with undercut margins, one of said grooves extending the full length of one arm of said member, and the other extending from such first mentioned groove to the end 85 of the other arm; blades with dovetailed tongues, integral with said blades and fitting into said grooves; and means for securing the parts in assembled position.

2. In a separable square, the combination 90 of a right angled connecting member, having grooves with undercut margins, blades with dovetailed tongues, integral with said blades and fitting into said grooves; a notch in the edge of one of said tongues, adapted to receive and fitting the end of the other tongue, and means for securing the parts in assembled position.

PULASKI J. COOLEY.
In presence of—

JOHN M. RAUHOFF,
GUSTAV SCHULZ.
